Primary Examiner — Charles D Hanson(74) *Attorney, Agent, or Firm* — Luedeka Neely Group, PC(57) **CLAIM**

The ornamental design for a corpectomy spacer, as shown and described.

DESCRIPTION

FIG. 1 is a perspective view of a corpectomy spacer of our new design;

FIG. 2 is an anterior view of the corpectomy spacer of FIG. 1;

FIG. 3 is a posterior view of the corpectomy spacer of FIG. 1;

FIG. 4 is a right side view of the corpectomy spacer of FIG. 1;

FIG. 5 is a left side view of the corpectomy spacer of FIG. 1.

FIG. 6 is a top end view of the corpectomy spacer of FIG. 1; and,

FIG. 7 is a bottom end view of the corpectomy spacer of FIG. 1.

The broken lines in the drawings are included for the purpose of illustrating unclaimed features and form no part of the claimed design.
